CIGARETTE EXTINGUISHER

James B. Fisher, Pacific, Mo.

Application January 13, 1950, Serial No. 138,363

4 Claims. (Cl. 131—235)

1

The present invention relates to a cigarette extinguisher especially adapted to be used in connection with ash receivers of one kind or another. In referring to cigarettes, of course it will be understood that the principles of the invention can be adapted to other similar smoking articles, but, owing to the wide use of cigarettes, it is to be most abundantly used in connection with them.

Heretofore, many efforts have been made to provide ash trays that will extinguish cigarettes promptly without slow glowing and smoking thereof, and without the continued burning that is apt to cause fires. Among the difficulties with such cigarette receivers have been the fact that they were slow acting and not reliable, that they did not so contain the cigarettes as to take them out of sight, and that they required an unnecessary amount of mechanism to be effective.

The objects of the invention include the overcoming of the foregoing difficulties and the provision of a very simple cigarette extinguisher and ash receiver that is always dependable in operation and is inexpensive to manufacture. It will be seen that this extinguisher requires a minimum number of moving parts, with no levers or other operating members to be moved by the user. It employs the tubular principle, but without requiring a tube of such small diameter that the cigarettes become packed therein. It has retaining means to hold the cigarette to be extinguished, within the tube, but the retaining means cannot snag the cigarette to prevent proper expulsion thereof from the tube. Other features will appear from the description to follow.

In the drawings:

Figure 1 is a plan view of an ash receiver with the cigarette extinguisher thereon;

Figure 2 is a side elevation partly broken away of the extinguisher of Figure 1;

Figure 3 is an enlarged vertical section through the upper part of the receiver and through the cigarette extinguisher, taken on the line 3—3 of Figure 1;

Figure 4 is a bottom view of the upper parts of the ash receiver;

Figure 5 is a side elevation partly in section of the retaining means in the cigarette extinguisher;

Figure 6 is a sectional view through the cigarette receiver, showing its effect on cigarettes;

Figure 7 is an elevation of a modified form of ash receiver with the cigarette receiver mounted thereon; and

2

Figure 8 is a section on the line 8—8 of Figure 7.

The cigarette extinguisher of Figures 1—6 is here shown as mounted upon a receptacle 10. For illustrative purposes, this receptacle 10 is shown as having an upwardly extending top flange 11 (Figure 3) to receive what may be called the base portion 12 of the extinguisher. This base portion is circular, having an outer flange 13, by means of which it is fitted over the flange 11 of the receptacle 10. Inwardly of the flange 10, it has a downwardly extending conical chute portion 14 that terminates in a circular opening 15.

A plurality of brackets 16, here shown as three in number, are of arcuate shape, each being attached at one end to the underside of the conical portion 14 in such wise that its other end extends through the opening 15 and can be attached to a shield 17 that is also more or less conical in shape and is hollow. This shield has a lower dimension that is somewhat smaller than the opening 15, so that there is an annular passage 18 between the lower end of the shield 17 and the lower end of the conical portion 14 of the base. By the foregoing arrangement, the conical shield 17 is substantially rigidly supported upon the base member 12.

The conical shield 17 supports a tube 20 that is illustrated in vertical position. This tube preferably flares out at its upper end as shown at 21. Its lower end preferably has a cut-away 22 on one side and a vertical slit 23 on the opposite side, the result being that the effective bottom edge of the tube 20 is the top edge of the cut-away 22. The diameter of the tube 20 is slightly greater than the diameter of a cigarette. Owing to the construction that will be described, the minimum inner diameter of the tube 20 may be sufficiently great that a cigarette will freely pass through it without the possibility of becoming jammed therein and without the possibility of serious accumulation of tar on the interior of the tube. For example, the inner diameter of the tube 20 may be approximately $\frac{1}{8}$ of an inch, which is about $\frac{1}{8}$ of an inch greater than the diameter of a conventional cigarette.

Adjacent the lower end of the tube 20, there is a combination retainer and deflector. To this end, a cover member 25 is attached to or formed integrally with the lower end of the tube 20, and it covers the slit 23. A cross section of the cover 25 is approximately U-shaped, as indicated in Figure 4. Its upper end extends up beneath the hollow shield 17. A U-shaped swinging hanger

26, that may be made of wire or the like, has its ends swingably mounted in the sides of the cover 25, the cover and parts upon which it is mounted thereby comprising a support for the hanger. The mid-portion of the hanger 26 depends toward the bottom of the tube 20 and lies across the lower end of the slit 23, at which point it supports a roller 27. This roller is thus rotatable on the bight portion of the hanger 26 and extends through the slit 23 so that it enters the lower end of the tube 20 opposite the cut-away portion 22. A very light torsion spring 28 acts between the cover and the hanger 26, to urge the wheel to project into the slit 23 with its edge toward the axis of the tube 20.

The base may be provided with a suitable number of cigarette rests 30.

A modification of the mounting of this device is shown in Figures 7 and 8. This modification is particularly adapted to use on automobiles or the like whereon it may be mounted, for examples, on the instrument, steering column or the panel. In this arrangement, there may be a supporting ring or the like 35 that may fit over the open end of a receptacle or may be otherwise attached to the instrument panel or other suitable part. In this embodiment, the tubular part 20 and its assembly may be the same as the previous modification. It has the cut-away notch 22 at its inner end, and it has the slit 23 through which the wheel 27 projects. The wheel is rotatably mounted on the inner end of the hanger 26 and is yieldably urged toward the axis of the tube 20 by the spring 28. The part of the wheel 27 nearest the axis of the tube must be below the top edge of the notch 22, which top edge, in this sense, constitutes the bottom edge of the tube itself. In this modification, the tube 20 is mounted in an outer tube 38 that provides an extension 39 outwardly of the flaring end 21 of the tubular member 20. This extension 39 is adapted to receive a cigarette or the like and to support it at rest, as well as to aid in guiding it into the tube 20. The tube 20 may be suitably soldered or otherwise attached to the member 38, and that member, in turn, is secured to the supporting ring 35. A shield 40 extends upwardly from the tube 38 and extends within a short distance of the limits of the ring member 35 so as to provide a substantially arcuate space 41 through which ashes and the like may be discharged into the receptacle (not shown) to which the ring 35 is attached.

With this arrangement, it will be seen that the tube or extinguisher part is mounted at the side of the base, which latter is in the form of the ring 35. This type of device can be mounted at an angle to the vertical, and indeed can be mounted horizontally, but it obtains greater utility when mounted out of the horizontal because then ashes may be discharged against the downwardly flaring shield 40 so that they will pass into the receptacle upon which the supporting ring 35 is mounted.

Operation

Referring first to the principal embodiment of the invention, it will be seen that it has all the facilities of the usual ash receptacle in that it has the cigarette holders 30 and it has the base of the extinguisher so designed that the ashes may be discharged against the inwardly flaring conical portion 14 and pass through the annular passage 18 into the receptacle 10. The passage 18 is preferably designed to be too narrow to

receive a cigarette. Consequently, cigarettes that may be rested upon it rather than upon the rests 30 will not fall into the receptacle 10 and smolder therein.

In extinguishing, a cigarette is merely inserted into the tube 20 with its lighted end downwardly and dropped. The first cigarette inserted will fall down until its lower end engages the radially inwardly projecting portion of the wheel 27. The spring 28, although a very light hair type of spring, is of sufficient strength to cause the wheel 27 to support the cigarette within the tube. Owing to the close fit of the cigarette within the tube, the lack of an unobstructed oxygen course through the cigarette, and the usually cold temperature of the tube 20, the cigarette shortly will become extinguished.

When a second cigarette is put in above the first, the lower end of the second cigarette, upon being pressed upon the upper end of the first, causes the first cigarette to be forced down through the lower end of the tube 20. As illustrated in Figure 6, the cigarettes that are normally discarded are usually short so that they do not extend the full length of the tube 20, the total length of which is preferably almost the equal of the standard cigarette. A second cigarette, such as that shown at B in Figure 6, is likely to cause the first cigarette A to be discharged further down toward the receptacle 10, but it may not cause it to leave the tube 20. Then the second cigarette B, thus located in the tube with the cigarette A also in the tube, will become extinguished very shortly because the first cigarette A substantially blocks all passage of air through the tube. It has been found that the second cigarette in such instances will become extinguished in the matter of a relatively few seconds, and even quicker than the first.

When the third cigarette C is disposed in the upper end of the tube 20 and forced downwardly, it causes the first cigarette A to move down and become discharged into the receptacle. It has been found that the cigarettes A and B are likely to become somewhat fused together by the burning action of the lower end of the cigarette B prior to its extinguishment. However, the wheel 27 applies a force from the light spring 28 against the lower cigarette A opposite the notch 22. This force causes the lowest cigarette A to be deflected away from the axis of the tube 20, as is illustrated in Figure 6, so that as it is finally forced downwardly the deflecting action will break it away from the cigarette B and cause it to drop fully into the receptacle 10. In the meanwhile, the cigarette B will remain against the wheel 27 and will adequately restrict air flow through the tube 20 so that the cigarette C goes out very quickly.

The action of the modification in Figures 7 and 8 is the same.

In both, therefore, the tube 20 is the thing that extinguishes the cigarette, and that extinguishing action is particularly enhanced after one cigarette has been disposed within the tube. However, the tube 20 may be large enough with respect to the ordinary cigarette that tarring action on its inner wall is minimized. Heretofore, the tubular type of cigarette extinguishers have largely relied upon a snug fit of the cigarettes at least at some point within the tube to restrict the flow of oxygen and cause early extinguishment. The present arrangement can employ a looser tube with the minimization of sticking of cigarettes therein, either by their

own deformation or by the accumulation of foreign matter, and yet can provide for the quick extinguishment of cigarettes owing to the fact that a previously inserted cigarette acts as a contributing means to the restriction of oxygen flow through the tube. In this, the yieldable means at the lower end of the tube functions to retain the earlier deposited cigarette for the explained function.

But, further, the yieldable means at the discharge end of the tube acts not only as a retaining mechanism but also as an expelling or discharge mechanism to eject the lowest cigarette from the tube when it is fully moved toward the lower end of the tube. This latter action comes about because of the cooperation of the spring-urged retaining and pressure member 27 opposite to the cut-away portion 22 of the tube.

Of course the tube 20 has sufficient length to support any cigarette, however slightly used, that is disposed in it. Also, the receptacle 18 preferably should be long enough so that a very slightly used cigarette extending from the bottom end of the tube 22 at the point of discharge therefrom is not jammed against the bottom of the receptacle. In other words, the bottom of the receptacle should be in excess of a cigarette length away from the lower part of the tube 20.

It should be evident that modifications of the retaining means and other elements of this combination can be made. In this connection, it may be commented that the wheel 27 as a retaining means has a distinct advantage because its rotatability enables the cigarettes to be forced down with much greater ease than would be true with merely a non-rotatable spring-like member at this point, and it will not snag the cigarettes. Likewise, in certain cases, the receptacle may be dispensed with and the extinguished cigarettes may be discharged into the open as on a motor vehicle, for example.

All such modifications of details are contemplated within the claims to follow, together with such other equivalents as will be understood from a knowledge of the art.

What is claimed is:

1. In an extinguisher for cigarettes and the like, a member having a passage means therethrough slightly larger than the diameter of a cigarette, through which the cigarette may pass, yieldable cigarette retaining means including a roller having an edge extending into the passage means and yieldable means mounting the roller to hold its edge so, the yieldable means being adapted to apply a force to the roller sufficiently great to overcome the force of gravity on the cigarette but yieldable to a force applied to the cigarette to discharge it through the passage means.

2. In an extinguisher for cigarettes and the like, a member having a passage means therethrough slightly larger than the diameter of a cigarette, through which the cigarette may pass, yieldable cigarette retaining means including a roller having an edge extending into the passage

means and yieldable means mounting the roller to hold its edge so, the yieldable means being adapted to apply a force to the roller sufficiently great to overcome the force of gravity on the cigarette but yieldable to a force applied to the cigarette to discharge it through the passage means, the innermost part of the roller being below and opposite the edge of the member at the discharge end of the passage means, so that the yieldable member may laterally deflect the cigarette discharged through the passage means.

3. In an extinguisher for cigarettes and the like, a member having a passage means therethrough slightly larger than the diameter of a cigarette, through which the cigarette may pass, yieldable cigarette retaining means including a roller having an edge extending into the passage means and yieldable means mounting the roller to hold its edge so, the yieldable means being adapted to apply a force to the roller sufficiently great to overcome the force of gravity on the cigarette but yieldable to a force applied to the cigarette to discharge it through the passage means including a hanger for the roller, a pivotable support for the hanger, that is spaced from the axis of the roller, and spring means urging the hanger and roller toward the axis of the passage means.

4. In a cigarette extinguisher, a base adapted to fit over a receptacle, the base having a centrally and inwardly extending portion with an opening at its inner end, a downwardly and outwardly extending shield above the opening and having its lower edge spaced from the base to provide an ash slot; a tubular member mounted on the shield, and extending therethrough so as to have an outer end and an inner end, the tube having a length approximately that of a standard cigarette, one side of the inner end of the tube having a vertical slit, a cover of U-shaped cross section attached to the side of the tube over said slit and beneath the shield, a U-shaped hanger alongside the tube with a pivotal connection to the sides of the cover at the upper end of the cover, a wheel rotatably mounted on the hanger adjacent the slit, light spring means urging the hanger toward the tube to dispose the edge of the wheel through the slit, the lower edge of the tube opposite the wheel having a recessed portion, and means on the base for attachment to a container.
